UNITED STATES PATENT OFFICE.

OLOF P. SVENSSON, OF BROOKLYN, NEW YORK.

WATERPROOF CONTAINER.

Application filed August 1, 1927. Serial No. 209,982.

This invention relates to improvements in water proof containers.

The primary object of the invention is to provide a water tight receptacle which may be carried by a person while bathing or swimming and in which money and valuables may be securely kept.

Another object of the invention resides in a safety water tight container which is constructed of metal or other appropriate material, but which is relatively light in weight so as to float upon the surface of the water should the same accidentally become separated from the user.

15 A further object is the provision of a water proof container which may be carried about the waist of a wearer or as a hand bag, and which may be made in such shapes and designs as not to be objectionable to the appearance of a wearer.

A still further object is to provide a water proof container which includes an outer shell member, and an inner shell member removably supported from a cap and disposed within the outer shell member, the said cap serving to seal the outer shell member to exclude moisture from the inner shell member into which the valuables to be kept are placed.

A still further object is to provide an article of the above kind which is simple in construction, inexpensive of manufacture, and efficient for the purposes intended.

With these and other objects in view, the invention resides in certain novel construction and combination and arrangement of parts, the essential features of which are hereinafter fully described, are particularly pointed out in the appended claims, and are illustrated in the accompanying drawing, in

40 which:

Figure 1 is a top plan.

Figure 2 is a vertical sectional view on the line 2-2 of Figure 1.

Figure 3 is a vertical sectional view with 45 the parts in a separated position.

Referring more particularly to the drawing, the reference numeral 10 designates my improved water proof container in its entirety, and which includes a hollow body or outer shell 11 which has its bottom concave-convex, so that the body is deeper at its center than at its sides. The outer shell 11 is provided in its top with an opening 12, the walls of which are screw threaded as at 13 55 for co-acting engagement with the external

threads 14 provided on a flange 15 extending inwardly from a cover 16. An annular flange 17 extends beyond the flange 15 to overlie and seat within an annular recess 18 provided in the top of the outer shell. A gasket 19 is interposed between the flange 17 and the recess 18 to seal the joint therebetween against leakage.

The flange 15 is also provided with internal screw threads 20 for co-action with external 65 screw threads 21 provided on an inner shell 22, which is of a depth to snugly fit within the outer shell member. A gasket 23 is interposed between the inner shell 22 and the inner top wall of the cover 16. For the purpose of manually imparting a turning movement to the cover during the screwing and unscrewing of the same, to the outer shell member, I provide manipulating lugs 24 on the cover at diametrically opposite points. 70 These two lugs are grasped by the fingers of an operator during the turning of the cover with respect to the outer shell. 75

The outer shell 11 is provided with diametrically opposed eyes or loops 25 for receiving the ends of a strap by which the device may be carried either about the waist of a user or in the manner of a hand bag.

The outer and inner shells and cap may be constructed of any suitable light material 85 such as aluminium and may be die cast or stamped so that the same provides a relatively light structure. The container may be shaped in any suitable design and in a manner so that it displaces more than its 90 weight of water which makes the device buoyant so as to float upon the surface of the water should the same become accidentally separated from the owner.

In practice, the cover 16 is unscrewed from 95 the outer shell member, and the inner shell member in turn unscrewed from the cover, whereupon articles of value may be placed within the inner shell and the cover screwed thereon. The cover and inner shell now constitute a single unit which is in turn threaded to the outer shell member and screwed tight thereagainst and at which time the inner shell member is enclosed within the outer shell. In the event that water should seep 105 through the gasket 19 into the inner shell member or bilge compartment, it would not in any way reach the valuables within the inner shell, as it would be necessary for the liquid to pass the joint between the cover and 110

the inner shell, which joint is sealed by the gasket 23.

For ornamental purposes, the cover and body may have suitable designs engraved thereon, but this is optional. Also, in addition to the uses pointed out above, the outer shell may be utilized by campers as a container for cooking foods.

While I have described what I deem to be the most desirable embodiment of my invention, it is obvious that many of the details may be varied without in any way departing from the spirit of my invention, and I therefore do not limit myself to the exact details 10 of construction herein set forth nor to anything less than the whole of my invention limited only by the appended claims.

What is claimed as new is:—

1. A water proof container comprising an 20 outer shell member having an opening therein, the walls of said opening being screw threaded, a cover having a flange provided with external and internal screw threads, the external threads of said flange co-acting with 25 the threads of said opening, and an inner shell member having screw threads for co-

action with the internal screw threads of said flange.

2. A water proof container comprising an outer shell member having an opening therein, 30 the walls of said opening being screw threaded, a cover having a flange provided with external and internal screw threads, the external threads of said flange co-acting with the threads of said opening, an inner shell 35 member having screw threads for co-action with the internal screw threads of said flange, and gaskets respectively interposed between said cover and said outer and inner shell members.

3. A buoyant container comprising a rigid outer shell having an opening therein, a cover including a flange threadedly secured within said opening thereby forming a watertight compartment, and an inner shell threadedly 45 secured to the inner face of said flange, thereby forming another watertight compartment within the first mentioned compartment.

In testimony whereof I hereby affix my signature.

OLOF P. SVENSSON.
